UNITED STATES PATENT OFFICE.

AUGUST SUNDH, OF HASTINGS-UPON-HUDSON, NEW YORK, ASSIGNOR TO OTIS ELEVATOR COMPANY, OF JERSEY CITY, NEW JERSEY, A CORPORATION OF NEW JERSEY.

INTERWOVEN FLAT-BELT-DRIVE APPARATUS.

Application filed February 7, 1922. Serial No. 534,719.

To all whom it may concern:

Be it known that I, AUGUST SUNDH, a citizen of the United States, residing in Hastings-upon-Hudson, in the county of 5 Westchester and State of New York, have invented a new and useful Improvement in Interwoven Flat-Belt-Drive Apparatus, of which the following is a specification.

The invention relates to hoisting ropes or 10 cables for elevators in the cross-sectional form of a flat belt, and more particularly to the construction of the belt.

The object of the invention is to obtain a belt which shall have sufficient tensile 15 strength so as not to stretch under a desired load.

Another object is to obtain a combined tensile strength and frictional capacity so that the belt can neither stretch nor slide 20 under a certain load.

Other objects will also appear as herein-after set forth. My flat belt is applicable to any of the systems wherein a flat rope is used as a medium of hoisting cables or transmission of power, as in elevators, etc.

In the accompanying drawings:

Figure 1 is a view looking down on a sectional length of my cable or rope.

Figure 2 is a cross sectional view of my 30 rope or cable, taken on line *a—a*, Figure 1.

Figure 3 is a fragment of my rope or cable, showing the wires covered with a more or less yielding material.

Figure 4 is a section of a length of steel 35 wire, partly covered with a yielding material.

Figure 5 is a view showing the application of my ropes or cables to the traction sheave of a traction elevator; one of their ends 40 hitched to the car.

Figure 6 is a view showing my rope or cable over a ring on a traction sheave of a traction elevator, the ends of the rope fast to a car and counterweight.

Figure 7 is a view of a traction sheave, in the surface of which are grooves to offer resistance to the turning of the loose ring 45 on the sheave.

Similar numerals of reference refer to 50 corresponding parts throughout the different figures of the drawings.

Referring to the different views in which I have shown my improved belt, steel wires, 1, are used as the warp of a fabric belt, and

steel wires, 2, are used as the woof or weft; 55 the wires are covered with a fabric of cotton or asbestos, 3, or other kind of suitable fabric which has the capacity of being impregnated by an impregnating material when subjected to the process of impregnation and of retaining the impregnated substance. When the wires covered with the cotton or asbestos are tightly woven together, the cotton or asbestos is in effect tightly woven between the wires, and practically covers up the steel wires 60 and leaves the surface of the belt practically covered with cotton or asbestos, and the steel wires do not show through or, at least, not to any great extent. The result is that when the belt surface is in frictional contact 65 with a pulley or traction sheave of a traction elevator, the frictional engagement between the belt and sheave is much greater than it would be were the belt of woven wire alone.

Further, the life of the belt is noticeably 70 longer by reason of the cotton or asbestos, because, aside from the bending strain of the steel wires, there is very little wear on them. What wear there is takes place between the sheave and the soft cotton or asbestos fabric. Generally, the belt is woven first, and afterwards it is placed in a vacuum chamber with hot impregnating material, and when impregnated, is withdrawn from the chamber, and allowed to cool. The belt 75 will look like the usual woven and impregnated brake liner for the brakes of automobiles. Of course, I realize that in the course of time in the use of my belt, the soft material of cotton or asbestos will wear, and may be at 80 that instant the steel wires will show through the cotton or asbestos, and come into contact with the surface of the traction sheave, in which event the wire may be found to wear very fast.

In order to provide against such 85 a contingency, I have provided a loose ring, 4, on the sheave, 5, see Figure 6. The ring may be made of some soft material, like leather for example, or it may be of a material like brake liners of an automobile. The belt runs over the loose ring and if 90 there is any slip between the sheave and belt, it generally takes place between the surface of the inside of the ring and sheave, consequently wear of the belt is prevented, 95 and large frictional engagement obtained at all times. On the surface of the traction sheave, 5, in Figure 7, I have shown grooves, 100

6, which serve to resist the slipping of the ring, 4, on the sheave; however, that feature is not so important, and will be used only in those cases where extraordinary loads will 5 be lifted by the belt. The belt may be connected to the elevator car and counterweight in any approved way. I have not gone into that especially, but have merely shown an ordinary simple hitch to indicate 10 the application of my belt. I also wish it to be understood that the belt may be woven and impregnated in various ways; the important thing is that it must have tensile strength, and such strength be distributed 15 through the belt in such a way that the belt will have tensile strength to carry the load imposed on it without stretching and making the belt of less width than when it is not under load. I do not limit myself to the 20 construction of woven belt herein shown. My conception of invention is that a woven belt can be made by a person skilled in the art of weaving belts in which the tensile strength of the belt is properly proportioned 25 and distributed so that the belt will keep flat under loads and the wires thereof be covered by the soft material. It may be that the soft material will be allowed to project out more on the wearing side of the 30 belt than on the other side, somewhat similar to a floor rug in that respect. I am aware that a loose ring around the traction sheave of an elevator to obtain friction and lessen wear is old, as patented to G. H. Reynolds, 35 761,401, May 31, 1904, Rope drive apparatus, but he uses the ring in connection with wire round ropes or cables, which cut their way through the ring, and, therefore, the ring as Reynolds contemplated using was

useless for the purpose. But, I have found 40 in experimentation that a ring used in connection with a flat belt of steel wires and especially with my improved flat belt, will last a long time, and is of great value for the purposes herein referred to. I believe 45 that it is new to make use of a loose ring on a traction sheave in connection with a flat belt of interwoven steel wires and cotton or asbestos.

What I claim is:—

1. A traction sheave, an interwoven wire flat steel belt suspended over said sheave, and a counterweight on one end of the belt, and an elevator car on the other end, and an annular ring larger in diameter than the 55 traction sheave, between the surface of the traction sheave and the surface of the belt.

2. In a belt for traction elevators, the combination of a plurality of wire cables adapted for obtaining tensile strength and plurality of wire cables for holding the cables of tensile strength in relative places, and a woven fabric of soft material interwoven 60 in said wire cables.

3. In a belt for traction elevators, the combination of a plurality of wire cables adapted for obtaining tensile strength and a plurality of wire cables for holding the cable of tensile strength in relative places, and a woven fabric of soft material interwoven 65 in said wire cables, said soft interwoven fabric being impregnated with material to cooperate with the soft material for obtaining friction.

In testimony whereof, I have signed my 70 name to this specification.

AUGUST SUNDH.
